UNITED STATES PATENT OFFICE.

LORENZO S. GRAVES, OF ROCHESTER, NEW YORK.

ELEVATOR-GUIDE.

SPECIFICATION forming part of Letters Patent No. 394,768, dated December 18, 1888.

Application filed August 22, 1888. Serial No. 283,415. (No model.)

To all whom it may concern:

Be it known that I, LORENZO S. GRAVES, of Rochester, in the county of Monroe and State of New York, have invented certain new and useful Improvements in Elevator-Guides; and I do hereby declare the following to be a full, clear, and exact description of the same, reference being had to the accompanying drawings, forming part of this specification, and to the figures and letters of reference marked thereon.

In the construction and operation of elevators, particularly those adapted to carry passengers and running at high speed, it is very desirable that the car be supported and guided so as to move as smoothly and noiselessly as possible and no lateral motion be permitted, and in endeavoring to accomplish this great difficulty has been encountered in constructing and keeping the vertical guideways perfectly true, by reason of the warping of the wood of which they are generally composed, or if of metal in so keeping the joints of the sections in line that there will be no jar when the car is passing over them.

My present invention has for its object, therefore, to provide a guide to be applied to the car that will automatically adapt itself to any inequalities in the way, and, taking up the thrust usually imparted to the car, will guide the latter truly and smoothly at no matter what speed it is operated; and to this end it consists in the hereinafter-described device, the novel features being pointed out particularly in the claims at the end of this specification.

In the accompanying drawings, Figure 1 is a view of a portion of an elevator-car and its way, showing the application of my invention thereto. Fig. 2 is a side view of one of the guides detached; Fig. 3, a top plan of the same; Fig. 4, a section on the line *xx* of Fig. 3.

Similar letters of reference in the several figures denote similar parts.

The guides ordinarily in use on elevators are usually applied to the top and bottom of the elevator-car, (represented by the letter A in the drawings,) arranged to engage with way B on the side timbers or supports, C, forming the well, and guiding the car so as to prevent swinging or lateral movement in

either direction; and my improved guide is adapted to be applied in the same manner, the invention lying in its improved construction, whereby the car will be less susceptible to jars and shocks caused by unevenness in the way.

One of these guides is shown clearly in Figs. 2, 3, and 4, and it consists, generally, of a base or casting, 1, provided with a flat portion, 2, 6 in which are provided elongated slots 3 3 for the passage of the bolts 4 4, for securing it to the timbers of the car and permitting limited adjustment on said car, as will be understood. Formed in the casting is an open-sided recess 6, substantially conforming in shape to the way at the side of the well—in the present instance rectangular and slightly larger than said way—and in each of the sides and the back of this recess are provided perforations 5 (see Fig. 4) 7 and suitable sockets, 6 6, preferably formed in projecting portions 7, for securing lightness, and on either side of the perforations 5, as shown.

Inside the recess on the base-casting and forming the operating-surfaces of the guide are presser-plates 8 8, each, as in Fig. 4, preferably provided with flanges 9, projecting over the edges of the casting, as shown, and at or near the center with a perforation, 10, countersunk on the outside. Projecting through this perforation is a bolt, 11, having a conical head corresponding to the countersink and normally below the face of the plate, and its body portion, which passes through the perforation 5 in the casting, is threaded, and upon it is secured a nut, 12, and set-nut 13, as shown, while a pin, 20, passed through a perforation in the end of the bolt, prevents the accidental removal of the nuts. Springs 14 are inserted 9c in the sockets in the main casting and operate to press the plates 8 8 out toward the center of the recess, the motion being limited by the nuts on the bolts, constituting stops which can readily be adjusted.

In use these guides are adapted to be secured to the top and bottom of the elevator-car, as shown, or to the top alone, if desired, and the nuts 12 and 13 are so adjusted as to allow the springs to hold the plates lightly 10 against the way, as in Fig. 3, and guide the car in its movements. Should there be any

unevenness in the way, either on the front or sides, caused by improper construction or warpage, the car in passing such points would not be affected by them, but the springs would 5 take up the thrust in all directions, as only spring-pressed surfaces are in contact with it.

The novel and advantageous feature of supporting the presser-plates at the center, providing them with the countersunk perforation, and employing the correspondingly-shaped bolt-head is that a universal motion is permitted the plates and the sides or ends permitted to move in any direction, so that in moving over an enlarged portion of the 15 way the ends first coming in contact with it will be moved back, tilting the plate or plates on the bolt-head and permitting first one and then the other spring to be compressed; or, in the event of the obstruction occurring at 20 the side of one of the plates, the latter will be permitted to tilt on the bolt in the same manner.

By the employment of the herein-described guide the unevenness of the way is fully compensated for by the springs, which are interposed on all sides, and, as I have practically demonstrated in a large number of high-speed elevators, materially improves their operation, reduces the noise, and lessens the jar.

30 It is obvious that instead of employing the spiral springs, as shown, leaf or any other kind could be employed; or a single spring employed for each plate, with the ends engaging the presser-plates on opposite sides of the pivoted point and the central portions and against the side of the recess in the casting, could be used with the same effect.

I have not deemed it necessary to show but one of the presser-plates in section, as they 40 are all constructed and operated in the same manner.

It will be understood that if instead of the rectangular guide shown a triangular one should be employed it will be necessary to 45 employ but two of the presser-plates with their faces disposed parallel to the surface of the way on which they operate.

Numerous modifications will occur to those skilled in the art, and I do not therefore desire to be confined to the details shown.

50 I claim as my invention—
1. In a guide for elevators, a presser-plate having a central support and springs on opposite sides of said support, substantially as described.

55 2. In an elevator-guide, the combination, with the casting having the open-sided recess formed therein, of the three spring-

pressed presser-plates located therein and forming the sides thereof, arranged to co-operate with the way, substantially as described. 60

3. In an elevator-guide, the combination, with the casting or support, of a presser-plate, a bolt for securing it to the casting, and springs between said plate and support located on opposite sides of said bolt, substantially as described. 65

4. In an elevator-guide, the combination, with the support, of a presser-plate, a bolt connecting the support and plate, permitting 70 the independent oscillating movement of the latter, and springs between the plate and support on opposite sides of the bolt, substantially as described.

5. In an elevator-guide, the combination, 75 with the support, of a presser-plate having the countersunk recess, the bolt having the head co-operating with the said recess and connecting the plate and support, and springs interposed between said plate and support, 80 substantially as described.

6. In an elevator-guide, the combination, with the support having the sockets therein and the perforation between them, of the presser-plates having the recess countersunk 85 on the inside, the bolt passing through the plate and support, and the springs in the sockets, substantially as described.

7. The herein-described guide for elevators, having universally - movable presser - plates 90 adapted to co - operate with the way and springs for pressing them in contact with it, substantially as described.

8. In an elevator-guide, the combination, with the main casting having the open-sided 95 recess, of the three presser-plates mounted therein, springs for holding them away from their support, and stops for limiting their motion in this direction, substantially as described. 100

9. In an elevator-guide, the combination, with the support, of a presser-plate, springs for holding it away from the support, and a bolt and adjustable nut for limiting its movement, substantially as described. 105

10. In an elevator-guide, the combination, with the support, of one or more presser-plates having flanges projecting over the ends of the support, springs for moving the plate or plates away from the support, and a stop or stops 110 for limiting the movement of the plate, substantially as described.

LORENZO S. GRAVES.
